(57) **CLAIM**

The ornamental design for an electric trimmer, as shown and described.

DESCRIPTION

FIG. 1 is a perspective view of top, front and left side of an electric trimmer showing our new design;

FIG. 2 is a left side view thereof;

FIG. 3 is a right side view thereof;

FIG. 4 is a front view thereof;

FIG. 5 is a rear view thereof;

FIG. 6 is a top view thereof;

FIG. 7 is a bottom view thereof.

FIG. 8 is a perspective view of a top, rear and right side thereof; and,

FIG. 9 is another perspective view of top, front, and left side thereof with detachable battery.

The broken line showing of the electric trimmer is for the purpose of illustrating portions of the article and forms no part of the claimed design.

The handle of the electric trimmer is shown broken in the middle in FIG. 2, FIG. 3, FIG. 4 and FIG. 5 for ease of illustration.
